UNITED STATES PATENT OFFICE

128,512

DESIGN FOR A SLIPPER

Clark L. Wilcox, Brockton, Mass., assignor to Field
and Flint Co., Brockton, Mass., a corporation of
Massachusetts

Application June 11, 1941, Serial No. 101,399

Term of patent 14 years

To all whom it may concern:

Be it known that I, Clark L. Wilcox, a citizen
of the United States and a resident of Brock-
ton, county of Plymouth, Commonwealth of
Massachusetts, have invented a new, original,
and ornamental Design for a Slipper, of which
the following is a specification, reference being
had to the accompanying drawing, forming part
thereof.

In the drawing:

Fig. 1 is a top plan view of a slipper, showing
my design; and

Fig. 2 is a side elevational view of the same.

I claim:

The ornamental design for a slipper, substan-
tially as shown.

CLARK L. WILCOX.
